UNITED STATES PATENT OFFICE.

CHARLES W. CHIPPS AND ALBERT L. HARTMAN, OF HACKER VALLEY, WEST VIRGINIA.

DESIGN FOR A SAW-SETTING TOOL.

52,428.

Specification for Design.

Patented Sept. 17, 1918.

Application filed July 15, 1916. Serial No. 109,576. Term of patent 14 years.

To all whom it may concern:

Be it known that we, CHARLES W. CHIPPS and ALBERT L. HARTMAN, citizens of the United States, residing at Hacker Valley, in the county of Webster and State of West Virginia, have invented a new, original, and ornamental Design for a Saw-Setting Tool, for which the following is a specification, reference being had to the accompanying drawings, forming part thereof.

Figure 1 is a front elevation;

Fig. 2 is a side view; and

Fig. 3 is a side view taken from the opposite side of Fig. 2, showing our new design.

We claim:

The ornamental design for a saw setting tool, as shown.

CHARLES W. CHIPPS.
ALBERT L. HARTMAN.

Witnesses:

W. K. BRIGHT,
W. M. ARBOGAST.
